US00D765127S

(12) **United States Design Patent** (10) **Patent No.:** **US D765,127 S**
Kim et al. (45) **Date of Patent:** **** Aug. 30, 2016**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Ye-Jin Kim**, Seoul (KR); **Ji-Hyun Ahn**, Seoul (KR); **Jae-Myoung Lee**, Seoul (KR)

(73) Assignee: **Samsung Electronics Co., Ltd.**, Suwon-si (KR)

(**) Term: **14 Years**

(21) Appl. No.: **29/525,335**

(22) Filed: **Apr. 29, 2015**

(30) **Foreign Application Priority Data**

Feb. 27, 2015 (KR) 30-2015-0010287

(51) **LOC (10) Cl.** **14-04**

(52) **U.S. Cl.**

USPC **D14/487**; D14/492

(58) **Field of Classification Search**

USPC **D14/485-495**

CPC **H04M 1/72519; H04W 4/18**

See application file for complete search history.

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The broken lines in the figures show portions of the display screen or portion thereof with graphical user interface which form no part of the claimed design.

1 Claim, 1 Drawing Sheet

How are you? 12:33

LONDON
Wed, January 15

22° 24° 17° 20° 27°
22° 23° 14°
22° 23° 18°

Partly sunny

A line graph showing daily high and low temperatures for London from January 16 to 21. The y-axis represents temperature in degrees Celsius, with a dashed line for high temperatures and a solid line for low temperatures. The x-axis shows the dates: Thu 1/16, Fri 1/17, Sat 1/18, Sun 1/19, Mon 1/20, and Tue 1/21.

Date	High Temp (°C)	Low Temp (°C)
1/16	22	15
1/17	24	9
1/18	17	7
1/19	20	10
1/20	27	20
1/21	22	10
